United States Patent Office.

JAMES PARISH, OF CHICAGO, ILLINOIS, ASSIGNOR TO HIMSELF AND
JOSEPH CRETET, OF SAME PLACE.

Letters Patent No. 72,671, dated December 24, 1867.

IMPROVEMENT IN DRAG-HOOKS.

The Schedule referred to in these Letters Patent and making part of the same.

TO ALL WHOM IT MAY CONCERN:

Be it known that I, JAMES PARISH, of Chicago, in the State of Illinois, have invented a new, improved, and useful Grapnel or Drag-Hook; and I do declare that the following is a full, clear, and exact description of the construction and operation of the same, reference being had to the accompanying drawings, making a part of this specification, in which—

Figure 1 is a top view, having a portion cut away.

Figure 2 a perspective view.

Like letters refer to like parts in both figures.

The object of my invention is to provide a grapnel or drag-hook, to be used in recovering anchors, chains, and other articles lost in the waters, which will in use retain its upright position, which will be drawn into the sand, which usually accumulates over lost articles, down to the hard bottom on which the article lost rests, and also to so construct my grapnel that the depth to which it will enter the sand and earth can be readily adjusted and regulated.

To enable others skilled in the art to make and use my grapnel, I proceed to describe its construction and operation.

I make my grapnel or drag-hook of iron chiefly, and in the form of an anchor, A being the shank, B the flukes, b the point. The shank A may be about four and a half feet long, three inches wide, and one and a half inch thick, and I usually make the edges square. The flukes B are made broad, with edges somewhat sharp, so that it can be more easily drawn through sand and other earthy deposit. The points b are made of steel, the outer surface being somewhat convex. I make the flukes B of such shape that their outer line forms a half circle. At g I attach two broad guards or floats, C, to the shank A loosely, by means of a pin, or in any other suitable manner. These guards or floats are notched at one end, as shown at f, while the other end is cut, as shown, to permit the guard to pass over the flukes B. In the flukes B is a series of holes, a, in which a pin may be used for the purpose of regulating the position of the guards. By means of these guards the depth to which the fluke enters the sand can be easily regulated, the broad surface of the guard preventing it from passing much below the surface of the sand. By removing the guards, more than half the grapnel will be drawn into the sand in use. Through the shank A, and a short distance from the end, I pass an iron rod, c, about four and a half feet long and one and a quarter inch in diameter, the hole through which it passes being somewhat larger than the rod c, and allowing it to move freely. On each arm of this rod I place a roller, D, being about eight inches in diameter at the outer end, and somewhat smaller at the other end. These, must be made so as to revolve readily on the rod c, and should have a little lateral motion. They may be made of wood, properly bound with iron, and are held upon the rod c by means of a pin, or other suitable means, as desired.

These arms, constructed as described, have a double use—they keep the grapnel always in an upright position, and facilitate its passage over obstructions. The chain or rope used with the grapnel may be attached at d. At the other end of the grapnel I provide a place, e, to which I attach a rope, provided with a buoy, so that, if the grapnel becomes entangled or obstructed, it can be readily withdrawn.

The rod c, corresponding to the stock of an anchor, should be made of the best wrought iron, so that, if it comes in contact with an anchor or other substance, it will not break; it may be bent in use. The outer ends of the arms D should be heavily ironed, to protect them and to give them weight.

The inner edges of the flukes B, being made sharp, render this drag-hook more efficient than any now in use, as their sharp edges will catch and hold in many cases, when other forms in use would slip and be useless. The points b will, from their form, easily pass stones and similar obstructions against which they strike.

If it is desired to have the grapnel enter the sand and earth more than half way, remove the lower guard C, and, by placing the pin, against which the guard rests, on the upper side of the guard or float C which is left, the depth to which the grapnel will enter the sand and earth can still be regulated.

Having thus described my invention, what I claim as new, and desire to secure by Letters Patent, is as follows:

1. The rollers D D, in combination with the stock A, constructed substantially as and for the purposes specified.
2. The combination of the guards or floats C C with the flukes B B, constructed substantially as and for the purposes set forth.
3. The combination and arrangement of the stock A, flattened flukes B, and buoy-line shackle e, with the floats C C, substantially as and for the purposes specified.
4. A grapnel or drag-hook, constructed substantially as and for the purposes specified.

JAS. PARISH.
